UNITED STATES PATENT OFFICE.

VINCENZO RUGGIERO, OF WENDEL, WEST VIRGINIA.

FOLDABLE BOX.

1,307,757.

Specification of Letters Patent. Patented June 24, 1919.

Application filed November 16, 1918. Serial No. 262,838.

To all whom it may concern:

Be it known that I, VINCENZO RUGGIERO, a subject of the King of Italy, residing at Wendel, in the county of Taylor and State 5 of West Virginia, have invented certain new and useful Improvements in Foldable Boxes, of which the following is a specification.

The primary object of the invention is the provision of a box formed of any suitable 10 material and capable of folding in compact relation when not in use, readily set up in box formation when desired and forming a box of great strength.

A further object of the invention is to 15 provide a box possessing great strength and durability capable of being compactly folded and being formed of any desirable material and in any suitable size.

With these general objects in view and 20 others that will appear as the nature of the invention is better understood the same will be fully described in connection with the accompanying drawing in which like reference characters designate corresponding 25 parts throughout the several views.

In the drawings,

Figure 1 is a front elevation of the box set up for use partially broken away.

Fig. 2 is an end view thereof.

Fig. 3 is a transverse sectional view taken 30 upon line III—III of Fig. 1.

Fig. 4 is an end view of the box in its knocked-down folded arrangement.

Fig. 5 is a horizontal longitudinal section- 35 al view taken upon line V—V of Fig. 1.

Fig. 6 is a perspective view of the box folded and

Fig. 7 is a perspective view of an end portion with the box broken away.

40 Referring more in detail to the drawings, it will be noted that my box is illustrated as being formed of wood and is rectangular in cross section, being somewhat longer than it is wide. Equal sized substantially squared 45 ends 10 and 11 are connected by hinges 12 to the opposite ends of the bottom 13 of the box. The adjacent edges 14 and 15 of the said ends and bottom are correspondingly beveled permitting said edges to flatly contact each other when the ends 10 and 11 are 50 positioned perpendicular to the bottom 13 when the box is set up for use, it being understood that the ends are readily folded inwardly for lying flatly upon the bottom 13 by means of the hinges 12.

An upwardly projecting flange 16 is pro-

vided upon the forward edge of the bottom 13 of a height equal to the thickness of the ends 10 and 11, while an upwardly extending ledge 17 is provided upon the rear edge 60 of the bottom 13 of substantially twice the height of the flange 16.

By this arrangement, the ends 10 and 11 will lock between said flange 16 and ledge 17 when the ends are folded upon the bottom 65 13, such ends lying flush with the top of the flange 16 and permitting the front side 18 of the box which is hinged as at 19 to the flange 16 to be folded inwardly upon the ends 10 and 11 flush with the top of the ledge 17. 70 The rear side 20 of the box is connected by hinges 21 to the top of the ledge 17 and is positioned inwardly above the front side 18 when the box is folded.

The top of the box consists of a rib 22 connected by hinges 23 with the top of the rear wall or back 20 of the box and a lid 24 attached by hinges 25 to the forward edge of said rib 22. When the box is set up for use with the ends 10 and 11 at right angles to the bottom 13 between the flange 16 and lug 17, it will be seen that the ends are also positioned between the front side 18 and back side 20 of the box thereby holding the said 75 sides in box formation.

The rib 22 and the lid 24 are provided with marginal grooves 26 and 27 respectively adapted for receiving the upper edges of the ends 10 and 11 and the front side 18 of the box when the box is closed which imparts great strength and rigidity to the box structure as the lid and rib lock the sides and ends of the box together. The lid 24 may be swung to its open position upon the 80 hinges 25 without disturbing the closed position of the rib 22.

When the back 20 of the box is folded inwardly above the front side 18 thereof as heretofore described, the lid 22 may be also folded so as to lie upon the front side 18, permitting the lid 24 to be swung rearwardly upon its hinges 25 overlying the rib 22 and rear wall 20 as illustrated in Figs. 4 and 6 of the drawings. A hasp 28 is attached to the forward edge of the lid 24 100 adapted for engaging over a staple 29 projecting from the front side 18 and permitting the insertion of a padlock 30 in said staple for locking the box closed when desired. When the box is folded, the hasp 28 105 is engaged by a hook 31 carried by the ledge 17 while a similar hook 32 carried by the 110

flange 16 engages an eye 33 upon the adjacent edge of the rib 22. A notch 34 is provided in the inner edge of the lid 24 for accommodating the eye 33 when the box is closed as illustrated in Fig. 3 of the drawing. The staple 29 is accommodated within a recess 35 in the inner face of the rear side 20 and whereby the side 20 is supported suitably spaced from the front side 18 when the box is folded to accommodate the greater thickness of the rib 22.

By releasing the hasp 28 the lid 24 may be readily opened and the rib 22 swung upon its hinges 23 so that the ends 11 will be released for folding inwardly upon the bottom 13. The front side 18 is then folded inwardly upon the ends and the back 20 folded upon the front 18 with the rib 22 and lid 24 positioned as heretofore noted, permitting the hooks 31 and 32 to be engaged with the hasp 28 and eye 33 respectively, securing the box in its knocked-down folded arrangement. The box is then readily transported and readily set up for use by unfolding and positioning the parts thereof in the manner described.

What I claim as new is:—

1. A box comprising a bottom having a front flange and a rear ledge mounted thereon, a front and a rear side for the box hinged for inward folding respectively upon said flange and ledge, ends hinged upon the ends of said bottom normally positioned between said sides adapted for inward folding between the said flange and ledge, a rib hinged to the top of said rear side having marginal grooves overlying the upper edges of said ends when the box is set up for use, a lid hinged to the forward edge of said rib having marginal grooves overlying the upper edges of the ends and the other side of the box when closed, and retaining means connected between said ledge and lid and between said flange and rib when the box is in its knocked-down folded position.

2. A box comprising a bottom having a front flange and a rear ledge mounted thereon, a front and a rear side for the box hinged for inward folding respectively upon said flange and ledge, ends hinged upon the ends of said bottom normally positioned between said sides adapted for inward folding between the said flange and ledge, a rib

hinged to the top of said rear side having marginal grooves overlying the upper edges of said ends when the box is set up for use, a lid hinged to the forward edge of said rib having marginal grooves overlying the upper edges of the ends and the other side of the box when closed, a hasp upon the forward edge of said lid, a staple upon said front side adapted for connection with said hasp when the box is closed, the said rear side having a recess in its inner face adapted for receiving said staple when the box is folded, and a hook upon said ledge engaged with said hasp when the box is folded, adapted for retaining the box in its folded position with said staple in the recess and said rear side spaced from the front side with the folded rib seated upon the front side of the box.

3. A box comprising a bottom having a front flange and a rear ledge mounted thereon, a front and a rear side for the box hinged for inward folding respectively upon said flange and ledge, ends hinged upon the ends of said bottom normally positioned between said sides adapted for inward folding between the said flange and ledge, a rib hinged to the top of said rear side having marginal grooves overlying the upper edges of said ends when the box is set up for use, a lid hinged to the forward edge of said rib having marginal grooves overlying the upper edges of the ends and the other side of the box when closed, a hasp upon the forward edge of said lid, a staple upon said front side adapted for connection with said hasp when the box is closed, the said rear side having a recess in its inner face adapted for receiving said staple when the box is folded, a hook upon said ledge engaged with said hasp when the box is folded, adapted for retaining the box in its folded position with said staple in the recess and said rear side spaced from the front side with the folded rib seated upon the front side of the box, an eye upon the inner face of said rib, the said lid having an adjacently positioned notch adapted for accommodating said eye when the box is closed, and a hook upon said flange adapted for engaging the eye upon the box being folded.

In testimony whereof I affix my signature. 105
VINCENZO RUGGIERO.
